UNITED STATES PATENT OFFICE.

JOHN THOMSON, OF NEW YORK, N. Y.

ELECTRIC ZINC-FURNACE WITH INTEGRAL CONDENSER.

1,080,862.

Specification of Letters Patent.

Patented Dec. 9, 1913.

Application filed January 2, 1913. Serial No. 739,788.

To all whom it may concern:

Be it known that I, JOHN THOMSON, a citizen of the United States, and a resident of the borough of Manhattan of the 5 city of New York, in the county and State of New York, have invented certain new and useful Improvements in Electric Zinc-Furnaces with Integral Condensers, of which the following is a specification, reference 10 being made to the accompanying drawings, forming a part hereof.

This invention relates to the metallurgy of zinc and an object thereof is to produce metallic zinc fumes by the reduction of oxid 15 of zinc (ZnO) by carbon (C) and to subsequently condense said zinc fume to liquid metal. The heat necessary for decomposing the ZnO and C is preferably derived from an electric current passed through a "resistor".

The invention especially resides in particular means designed to accomplish the objects above stated.

The resistor above mentioned is comprised in a bed of carbon usually made of coke, which is disposed upon an open refractory grating and is confined by side walls. The size and shape of the carbon pieces as well as the depth, width and length 30 of the resistor bed may be variously modified to obtain any desired electrical resistance and intensity of current, which is brought to the two ends of the resistor by blocks of amorphous carbon or graphite situated in the end walls of the reaction chamber, that is, the resistor is interpolated between the two terminals.

The reaction chamber of the furnace is made of sufficient depth to receive the charge 40. which is placed directly upon and is sustained by the resistor.

The charge in its entirety is either a mixture or alternate layers of oxid of zinc and of carbon, preferably substantially the 45 relative proportions to effect when suitably heated practically the complete reduction and evolution of the charge in the forms of zinc fume (Zn) and monoxid of carbon (CO), that is to say, the amount of any inert residual matter unevolvable in the gaseous form will usually be of only a nominal or comparatively small amount.

As has already been intimated, the electric energy is transformed into caloric energy in the resistor bed of the furnace and

the heat thus generated, if the temperature is adequate, effects the decomposition of the superimposed mass, the following chemical reaction ensuing:

In the constructions illustrated the walls of the furnace immediately adjacent to the longitudinal sides of the resistor and its superimposed charge are more or less utilized to condense the zinc fume, to collect the liquid metal and to evacuate the residual gases. In other words, the longitudinal walls of the reaction chamber are somewhat utilized for the purpose of condensing.

The manner of connecting the carbon terminals to the bus-bars or main line cables are matters of importance and these parts have been improved in their details of construction.

The fundamental principles applicable to the condensation of zinc fume are well understood and need not be here repeated at length. When the $ZnO + C$ reaction is employed the resulting classical formula

is not precisely realized in a commercial furnace operation, that is, at the primary instant of the reaction, for there are always present sensible quantities of air and water which may be both intimately entrained and in chemical combination with the materials comprising the charge. Sulfur (S) may also be present to a deleterious extent and this is especially true if the carbon is in the form of ordinary coke. Some of the effects of oxidizing elements such as air and water may be to precipitate an objectionable portion of the fume in the form of "blue powder", or as "schmelz", or some combination of both, and these are things which this invention seeks to minimize.

Now, having regard to the foregoing, the several features of the invention will now be described in detail, reference being had to the accompanying drawings forming a part of this specification, and in which—

Figure 1 is a transverse center section, the lower or left hand portion of the figure denoting one manner of realizing the invention, while the upper or right hand portion of the figure denotes another manner of realizing the invention, the section being along either line B or C of Fig. 2; Fig. 2 is a lon-

itudinal center section as on the line A of Fig. 1, and illustrates at the opposite right and left hand portions different forms for realizing the invention; Fig. 3 is a detached, broken plan view of the carbon terminals, showing the attachment of the electrodes, and Fig. 4 is a diagram denoting modifications in the wall construction.

The restricted dimensions of Patent Office sheets do not permit a scale reduction from working drawings, hence the several figures are to be regarded as merely illustrative embodiments of the invention, indicative of the principles employed.

R is the reaction chamber, S the inner side walls of said chamber, T, T¹ the outer side walls, V the resistor, H the charge, D the carbon terminals, J the hearth, N, N¹ the zinc reservoirs, and W the residue sump.

The grate which forms the hearth is built from spaced refractory bars or plates which rest on ledges 6 formed in the tamped sole 7, and beneath the grate is the residue sump or chamber W. The grate bar spaces 8 are to be such that the pieces of resistor carbon will bridge them, but in any case they will serve to permit the inert ash or sintered residue, either by gravitation or by poking from above, to pass through and collect below. This also permits if desired that dissolvent material such as lime may be fed in at intervals and the temperature of the resistor be temporarily considerably increased above the normal, whereby a viscous or semi-liquid or even a liquid slag will be produced. If the slag is liquefied it may be tapped off, but means for doing this are not shown. In this wise the resistor may be run for a longer period of time when if the inert residue is collected upon a solid hearth. In fact the operation may continue until the ultimate accumulation of residue in the sump will be such that it becomes advisable to remove it and this will only occur at considerable intervals, days, weeks or even longer. Now, to effect this removal the resistor and the free grate bars may be taken out, the sump is emptied as by means of tongs, forks or shovels, and a new resistor is laid, all of which may be done quickly.

The carbon terminals D are built into the end walls X of the furnace. They preferably lie horizontally to the resistor with which their inner ends make contact. These rods are preferably beveled back from the vertical, as 9, Fig. 2, whereby the weight of the overlying material tends to maintain intimacy of contact between them and the carbon bed. In prior practice the terminals have been carried entirely through and beyond the outer faces of the furnace walls with the disadvantage of loss in heat radiation, requiring a considerably greater length of carbon, interfering with the application of wall bracing and increasing the electrical

resistance between the main line cables and the impingement at the resistor. These objections are largely overcome by applying to the terminals copper strips, as 10, Figs. 2 and 3, and housing them within the masonry, as shown, except only the thin projecting ends to which the bus-bars or cables are connected, as indicated by the power circuit P. When copper electrodes are applied in the manner shown a very large area of contact is obtained, insuring an equal flow of energy to all portions of the terminals. While the inner clamping portions of these electrodes may become quite hot, the loss in conductivity thus caused is easily compensated by providing an excess of section in the metal. On the other hand, such heat as may be conducted outwardly will, because of the large surface of the tang-ends 10^a, be readily dissipated to atmosphere.

The reaction chamber is virtually an open shaft in which the charge is maintained and usually without a cover. But it has been found advantageous not to load the resistor with an excessively deep supply of reacting materials. When the shaft is open the top of the charge may be said to serve as a portion of the upper surface of the furnace. By frequently applying thin layers of reacting materials, say at a rate to compensate the decomposition and slightly tamping the upper surface, air is adequately excluded and the heat loss by radiation is minimized. On the other hand, as a certain amount of pressure is developed in and above the reaction zone, there is opportunity for vapor, steam or dioxide of carbon to percolate upwardly away from the resistor, to mingle with the atmosphere, and the freedom of escape may be readily augmented at intervals by forcing bars or sharp pointed rods down into the charge. Consequently, according to this system, there is a more or less natural separation and evacuation of the pernicious volatile products of the reaction from that of the zinc fume and monoxid of carbon.

The volatilized products are caused to pass either from that portion of the reaction zone where the temperature is highest and directly and immediately from the sides of the resistor into perforations, ducts, slots, slits or spaces formed in the longitudinal side walls of the furnace. The boundary surfaces of said spaces diminish in temperature progressively with each and every increment of distance away from the active reaction zone and also from the sides of the resistor, but the temperature of the said spaces at their inlets will be nearly if not fully equal to that of the entering fume and gas. In the operation of this furnace and its integral condenser the temperature at or near to the impingement of the charge upon the resistor, the same as in the resistor itself, should be maintained suffi-

ciently high to prevent the existence of CO_2 . It is manifest, however, that the lower the temperature in the resistor the better will be the results from certain points of view.

5 Two different forms of condensing systems are shown in Figs. 1 and 2, and for simplicity of description each will be to a certain extent separately referred to. Thus, (see the upper or right hand half of Fig. 2) a portion of the inner side walls may be formed of several superimposed series of refractory round rods 12, the lower series being first laid and somewhat separated longitudinally. Then upon this lower series 15 the upper rods are stacked, thereby forming a staggered structure with a large number of intervening spaces 13. The rods are preferably laid so as to slope downwardly from the reaction chamber as shown, and if desired they may also be canted sidewise instead of lying at approximately a transverse right angle. These rods may also be arranged so as to occupy positions other than those just described. The inner ends 25 of these rods in fact provide a portion of the furnace walls, come into intimate physical contact with the sides of the resistor and may also come into contact with such portion of the charge as may be deemed to be subjected to a sufficiently high reaction 30 temperature. As a consequence of this construction and arrangement the inner ends of the rods will acquire and be maintained at or about the same temperature as that 35 of the resistor, and that portion of the charge to which they are adjacent. The temperature of the duct surfaces formed by the rods will progressively fall in passing from the reducing zone and with a rapidity 40 which will be a function of the material employed which may be such as fire clay or re-crystallized carborundum, carbon or the like.

The aim of the construction is to produce 45 in the walls a large number of lateral spaces, slits, ducts or perforations, each of restricted flow area but of considerable aggregate area and heat diffusing surface. The round rods meet this condition satisfactorily for 50 the reason that, aside from their nearly negligible line contacts, they do when staggered closely substantially present a minimum of flow area along their lineal spaces with a maximum of circumferential surface. It 55 is feasible, however, to practically realize the above mentioned conditions by a built-up or molded structure wherein there is a large number of fissures, perforations, or slits such as 14, shown in the lower or left hand half of Fig. 2.

Particular reference is now directed to Fig. 1 in which two ways are shown of dealing with the products received from the inner walls. Thus in the lower or left hand 60 side of said figure the outlet of the inner

series of wall slots is into a vertical chamber or gallery 15. Any coalesced or liquefied zinc will fall on to the sloped conduit 16 and flow into the zinc receptacle N which is disposed along the outside wall of the 70 furnace. The outer wall T is preferably constructed with a large number of outer down-sloping ducts, slots or slits 17 whose inner openings connect with the aforesaid gallery and whose outer openings lead to the atmosphere. Whatever is received in the gallery in the form of a gas or fumes is permitted or forced to escape from said gallery through these outer and consequently colder orifices. The result of this arrangement is that a second opportunity is afforded for extraction of heat from the fume and thus aid in the formation of liquid metal, in which case the latter will fall down along the surface 18 of the wall into 85 the underlying zinc receptacle while any residual gas may mingle with the air or be burned to CO_2 .

In the upper or right hand portion of Fig. 1 the construction and function of the inner wall S is substantially the same as has already been described; but the vertical gallery is divided as by means of a suspended plate 19 into two sections, an inner 20, and an outer 18. The zinc receptacle N¹ is here 90 constructed within the confines of the furnace and immediately beneath the lower open ends of the aforesaid galleries. The outer right hand wall T¹ is formed in about the same manner as that of the left hand wall, except that the slope of its ducts or slits 22 is downwardly and inwardly, that is, toward the sectional gallery. Now, as indicated by the arrows, all of the products of the reaction evacuated into the inner gallery section 20 is forced to flow downwardly and into the zinc receptacle space and any remaining volatile matter must flow upwardly into the outer gallery section 18, from whence it enters the wall spaces 22, 100 and such liquid zinc as is produced in these spaces will flow back into the gallery and down to the reservoir.

A contingent advantage of a gallery such as 15, or a gallery formed of sections such as 20 and 18, is that if the reaction proceeds more intensely at one portion of the resistor than another, which in fact is likely to occur, the flow of the ongoing volatile products will to a material extent be compensated 115 or equalized.

When the invention is practised as shown by the right hand half of Fig. 1, the residual gaseous matter which leaves the outer ends of the slots 22 enters a chamber Q which 120 blankets all of the discharge ends of the perforations 22. From this chamber Q the atmosphere may be reached through side ports or a port, as 23, or from its upper end portion, as 24. This chamber is utilizable for 125

the collection of "blue powder" or oxidized residuals which may be intermittently withdrawn from the bottom of said chamber through openings or an opening such as 25. 5 Moreover, the top of this chamber may be provided with cups or a recess, as 0, having perforated or slitted bottoms as the plate 26. Pieces of broken carbon, as 27, can be placed in said cups to perform the function of a 10 final strainer or filter at the tail end of the condensing circuit.

Now, reverting to the main members of the condenser, it will be remarked that carbon is in some respects a preferred material 15 for forming the condenser rods or plates, but if rods or plates of this material were in contact with the ZnO of the charge they would soon be damaged, and unless electrically insulated from the resistor they would 20 be likely to shunt current from the latter. This objectionable feature can be avoided by utilizing short pieces of rods or plates formed of say carborundum, which are preferably placed next to both the resistor and 25 charge, as indicated by 28, Fig. 1.

To realize high effective thermal efficiency in the resistor it is important that the temperature in the sump W shall be as high as possible, or in the reverse way of 30 pressing it, that the difference of temperature as between the lower surface of the resistor and the upper surface of the sump sole i shall be as little as possible, whereby there will be little tendency for the flow of 35 the heat units to the sump and whereby there will be a maximum tendency for the heat units to flow upwardly and to the sides of the reaction chamber. Moreover, a high temperature is preferable for the residue, as 40 it serves to prevent the latter from caking when primarily of a sintery characteristic, or to keep the residue in a fluid state when it possesses a primarily fluid characteristic.

In order to resist chemical attack the sole 45 7 is preferably constructed in the main part of such material as tamped carborundum sand or a mixture of crucible graphite and clay. These materials, however, are good conductors of heat and the problem which 50 then arises is to provide effective heat insulation. There are several ways in which this may be accomplished. One manner of satisfactorily realizing effective prevention of thermal energy from the sump is here 55 indicated. For example, the outer portion, as 29, of the tamping material used for making the sole is mixed with a large proportion of broken or granular "kieselguhr", that is infusorial earth previously made up with a 60 binder and highly heated, thus producing a very porous structure; next to this are thin kieselguhr bricks, as 30, and surrounding all is a box of cellular asbestos board 31. The thickness of such an insulating belt or 65 sheathing need not usually exceed from

about four to six inches, whence the compression due to the overhead weight will be of negligible amount.

Attention is directed to the fact that all of the spaces, galleries or chambers can be 70 easily reached for inspection, cleaning or repair, which is an advantage of importance in the operation of a commercial plant.

It will be apparent to those skilled in the art that various modifications can be made 75 in the design without, however, departing from its spirit and essence. In justification of this averment it will suffice to point out as follows: Thus in the reaction chamber, side walls, instead of using small separable members, relatively large slabs, blocks or a solid tamped structure may be substituted in which perforations, slits or ducts can be numerously molded. In fact, the plan has 80 been considered of forming tamped carbo- 85 rundum walls in which cores are placed, the withdrawal of which would leave slits, or oil-soaked strips or pencils of wood, or sawdust, or paper tubes can be laid, the ultimate burning out of which, like straws in 90 bricks, would produce a highly porous structure. Indications of the foregoing are denoted in the diagram, Fig. 4, in which horizontal staggered slots 32 and vertical slits 33 are shown. Again in the same figure a 95 stack of very thin plates is indicated, 34, cemented together with interposed granular particles as 35, which would produce a structure containing a great number of slits having capillary and diffusive characteristics 100 of a high order.

What I claim is:—

1. An electric furnace having a horizontal carbon resistor, two sets of terminals each comprising a plurality of carbon terminal members the inner ends of said terminal members being in contact with the resistor and located within the walls of the furnace, the outer ends of said terminal members being located in the walls of the furnace and 105 two sets of metallic strips which protrude from the walls to the exterior of the furnace, one set of said metallic strips connecting the outer ends of carbon members constituting one set of terminals and the other set of said 110 metallic strips connecting the outer ends of carbon members in the other set of said terminals.

2. In an electric zinc furnace having perforated reaction chamber walls contiguous 115 and connected to vertical extraneous spaces or galleries, the combination therewith of an underlying receptacle for receiving products of the reaction.

3. An electric zinc furnace having reaction chamber side walls provided with a plurality of outwardly extending side openings, a connecting portion having vertical space or spaces through which products of the reaction pass downwardly after having 125 130 135

passed the chamber side wall openings, and another space or spaces through which portions of the products of the reaction flow upwardly and subsequently pass to the atmosphere.

4. A furnace having reaction chamber walls and outer walls with vertical spaces or galleries between them, the reaction fume producing chamber being located between the chamber walls.

5. A condenser of the class described comprising the reaction chamber walls of a furnace and outer walls and having interposed between said walls vertical up-flow and down-flow spaces or galleries.

6. A condensing apparatus having vertical down and up-flow spaces or galleries located between walls each of which are provided with perforations that slope inwardly and downwardly.

7. In an electric zinc furnace, the combination with a resistor supported upon an open grating, of a residue sump, a tamped sole and a sheathing therefor, highly impervious to heat conduction.

8. An electric zinc furnace having perforated walls at the sides of the reaction chamber through which products of the reaction can pass, each of said walls being provided with a blanketing chamber which receives the residual gaseous products of the reaction and from which chambers said gaseous products can pass to the atmosphere.

9. An electric furnace having terminals at opposite ends, an electrical resistor be-

tween the terminals and a blanketing chamber in the side walls thereof.

10. A combined electric furnace of the resistor type and a fume condenser having in the walls a blanketing chamber between which and the reaction zone in the furnace the condenser is located.

11. An electric furnace having a resistor, a condenser arranged to receive the products of reaction through the side walls of the resistor-containing chamber and a blanketing chamber arranged to receive the residual gaseous products of the reaction after metallic fumes have been condensed to liquid metal.

12. In a combined furnace for producing metallic fumes and a condenser for receiving and condensing said fumes, the combination of a resistor, openings in the side walls of the reaction chamber through which openings the products of the reaction pass directly to the condenser from which residual gaseous products can pass to a blanketing chamber and thence to the atmosphere, the blanketing chamber being arranged in the side wall of the furnace and the condenser above referred to being located between the blanketing chamber and the reacting chamber.

This specification signed and witnessed this 31 day of December A. D. 1912.
